DUAL TRAFFICWAY

Joseph B. Strauss, San Francisco, Calif.; Annette Strauss, John Sparks, and Henry C. Clausen executors of said Joseph B. Strauss, deceased

Application November 9, 1937, Serial No. 173,620

3 Claims. (Cl. 238—5)

This invention relates to improvements in dual trafficways and, more particularly, to the structural arrangement of rails and treadways on roadbeds.

5 Among the objects of the invention is to provide a traffic way adaptable to the column use of flanged railway rolling stock and motor vehicles adapted to highway traffic on resilient tires.

Another object is to adapt the conventional 10 railway roadbed to dual traffic of this nature without disturbing the cross ties, ballast, switches, and other standard equipment.

Another object is to reduce the overhead expense of railways and increase the margin of 15 safety for high speed motor traffic by bringing it under the control of block systems, train dispatching, easy grades, underpasses, and the other safety measures controlling railway traffic.

Other objects and advantages will appear as 20 the description progresses.

The ever increasing congestion of urban population necessitates a corollary rapid transit means to relieve peak loads for local distribution. There is the further necessity for high speed 25 passenger and freight motor units for long hauls at shorter intervals intermediate the running time of heavier train schedules to avoid long waits and overhauling.

In this specification and the accompanying 30 drawing the invention is disclosed in its preferred form. But it is to be understood that it is not limited to this form, because it may be embodied in other forms within the purview of the claims following the description.

35 In the one sheet of drawings:

Fig. 1 is a cross section of a conventional railway roadbed having this invention incorporated therewith.

Fig. 2 is a plan view of a portion of the same.

40 Fig. 3 is a side elevation of a section of the same.

Fig. 4 is an enlarged detail in cross section taken on the line IV—IV Fig. 3.

In detail, the construction illustrated in the 45 drawing, referring first to Fig. 1, comprises the conventional roadbed 1, having the cross-ties 2 embedded therein and ballasted in the usual manner. The conventional steel rails 3, 3 are laid on top of the cross-ties 2 to which they are held by the spikes 4, 4. It is the general practice to interpose steel plates, such as 5, between the bases of the rails and the cross-ties to prevent the rails from cutting into the ties and to hold the spikes in proper position.

55 The present contribution to the art relates

particularly to the parallel treadways 6—6 on one or both sides of each of the rails 3, 3. These treadways are preferably composed of reinforced concrete in prefabricated sections laid end to end in lengths determined by convenience in handling or consistent with the length of the standard rails 3, to match the spacing of the cross-ties 2.

In forming these sections 6, the length of angle bar 7 is placed in a mold, not shown, with the base angle 8 resting upon the bottom of the mold. The length of T bar 9 spaced from the angle bar is similarly placed in the mold. The reinforcing bars 10—10 are then placed within the mold in spaced relation to each other, the angle bars 7 and 9, and the bottom of the mold. Proper concrete composed of cement and aggregates is then poured into the space between the angle bars 7 and 9 and the bottom and opposite ends of the mold. This structure lends itself to rapid mass production methods. After the preliminary set of the concrete, the angular end and bottom mold, not shown, can be removed and the sections 6 permitted to cure, which releases the molds for further duplication 25 of the sections. The external flange 11 of the T bar 9 is perforated or notched to receive the spikes 12, driven into the cross-ties 2, to hold the treadway sections 6 in spaced relation to the adjacent rails 3, as in Fig. 3.

At switches, crossings, and intersections the surface of the adjacent sections 6 are inclined as at 13 to the level of the rails 3 or the surrounding pavement where the highway vehicle leaves the railway. The width of each and the spacing of the treadways 6 will be determined by the wheel gauge and placement of the pneumatic tires of the highway vehicles running thereon. For dual wheel arrangement, see my co-pending application entitled "Railways", filed 40 March 29, 1937, bearing Serial No. 133,600.

Referring to Fig. 1, the treadways are placed to accommodate a special form of vehicle having independently steered and driven wheels 14, 14, with a relatively wide wheel gauge and a corresponding placement of the treadways, which are wider at the top 6 than the form shown in Fig. 4 adapted to lighter traffic. The vehicle shown is a high speed coach or motorbus, mounted upon the pneumatic tires 14, 14 tracking on the treadways 6, 6.

The coach is provided with the retractable pilot truck having the flanged wheels 17, 17 on the axle 18 extending between the brackets 19, 19 pivoted to the forward end of the traction trucks of the 55

coach. When running on the railway, as in Fig. 1, the pilot truck engages the rails 3, 3 to guide the vehicle and maintain the alignment of the tires on the treadways 6, 6. When the vehicle is manually steered, as on the highway, the pilot truck is retracted. For further particulars regarding this dual steering gear see my co-pending application filed November 30, 1937, entitled "Rapid transit systems" bearing Serial Number 10 177,215.

In precasting the sections of the treadways 6 as described, it is desirable to pour the concrete from above so that the rough aggregate will remain at the surface to improve non-skid and 15 tractive efficiency; the richer grout gravitates to the lower levels to enclose the reinforcing bars 10 in a denser and less pervious stratum. For traffic by lighter vehicles, the side bars 7 and 9 may be omitted, but they give great stability to the treadways for the heavier high speed vehicles which 20 may deflect treadways of less strength. "Concrete" as used herein is intended to include bituminous mixtures and other suitable substances.

The traction surfaces of the sections 6 can be brought up level with the tops of the rails instead 25 of below as shown, if desired, to avoid the necessity for the inclines 13. The width of the treadways can be increased, as in Fig. 4, and properly banked on curves in accordance with 30 engineering practice. It is desirable also to give the top plane of the treadways a slight camber or crown to provide drainage and to take advantage of the tractive tendency of a rolling tire to climb to the top of a laterally inclined plane. 35 Any suitable form of rigid members may be substituted for the angle bars 7 and 9 which may be laid in continuous length with the concrete poured between, instead of in sectional lengths,

as shown, if desired. In elevated trams and similar structures not having cross-ties, the treadways can be otherwise supported. In the absence of the rails 3, the pilot wheels 17, 17 can be guided by either of the rigid bars 7 or 9; this is particularly advantageous where the elevated treadways are laid upon the ground or upon a paved highway.

Having thus described this invention, what is claimed and desired to be secured by Letters Patent is:

1. A duplex trafficway including the road bed and ballasted cross-ties and parallel rails of a conventional railway track; reinforced concrete runways adjacent and colinear with said rails, 15 said runways composed of independent end spaced sections, each section having lateral metal angle bar sides, one of said bars having a continuous lateral flange extending across and spiked to said cross-ties for easy placement and removal of said sections relative to said rails.

2. A trafficway including a base; and parallel interspaced runways consisting of prefabricated concrete sections laid end to end and having an angle bar forming one lateral side and an inverted T bar forming the other lateral side of each section.

3. A trafficway including a base; and parallel interspaced runways consisting of prefabricated concrete sections laid end to end and having a 30 coextensive angle bar forming one lateral side of each section, the horizontal flange of said angle bar extending under said section; and an inverted T bar forming the other lateral side of each section, one horizontal flange of said T bar 35 extending under said section and the opposite flange of said T bar being fixed to said base.

JOSEPH B. STRAUSS.
